UNITED STATES PATENT OFFICE.

FOREST CHENEY, OF CHICAGO, ILLINOIS, ASSIGNOR TO CHENEY TALKING MACHINE COMPANY, OF CHICAGO, ILLINOIS, A CORPORATION OF ILLINOIS.

SOUND-REPRODUCING MACHINE.

1,395,093.

Specification of Letters Patent. Patented Oct. 25, 1921.

Application filed February 13, 1919. Serial No. 276,712.

To all whom it may concern:

Be it known that I, FOREST CHENEY, a citizen of the United States, residing at Chicago, in the county of Cook and State 5 of Illinois, have invented certain new and useful Improvements in Sound-Reproducing Machines, of which the following is a specification.

This invention relates to sound reproducing machines and more particularly to an improved sound amplifier therefor.

As is well known to those skilled in the art, while the initial vibrations of the diaphragm of such machines potentially set up 15 all of the complex air vibrations necessary to reproduce the fundamental tones and overtones going to make up the character and tone color of the recorded sound of instruments or voices, said air vibrations are 20 nevertheless very weak and must be amplified and strengthened in order that the recorded sounds will be developed and reproduced in sufficient volume.

I have discovered that the volume of 25 sound which can be reproduced by a sound box and tone arm of a given size may be greatly increased by conducting the sound waves from the tone arm through a cubical distributing chamber and therefrom by a 30 plurality of outlets the area of each of which is less than the area of the cubical chamber, the effect of this arrangement being to control the sound by providing a slightly restricted aperture from the cubical 35 chamber to the outlet. I prefer to employ such a chamber in combination with a plurality of amplifiers each comprising a mechanical throat, orchestral sections and a violin resonator such as described in Letters 40 Patent of the United States No. 1,170,800 and No. 1,170,801, granted to me on February 8, 1916.

One of the objects of my invention is to provide a talking machine with a plurality 45 of amplifiers so constructed and arranged as to increase, in a novel manner, the volume of the reproduced sound.

Another object of my invention is to provide a talking machine with a distributing 50 or tone chamber into which the sound is delivered from the tone arm and from which it is directed through a plurality of outlets, which outlets are in connection with the usual amplifiers or resonators. The distributing chamber which I have found most

desirable for the proper reproduction of sound is a cubical one, and it is with the cubical chamber that the outlets communicate.

These and other objects of my invention 60 are accomplished by providing a sound reproducing machine having a distributing chamber, a plurality of resonators and connections between the distributing chamber and resonators comprising orchestral sections and mechanical throats. 65

In the drawings:

Figure 1 is a horizontal sectional view on line 1—1 of Fig. 2, showing the preferred embodiment of my invention, 70

Fig. 2 is a sectional view on line 2—2 of Fig. 1,

Fig. 3 is a section on line 3—3 of Fig. 1,

Fig. 4 is a section on line 4—4 of Fig. 2, and

Fig. 5 is a section on line 5—5 of Fig. 1.

This invention is an improvement over that shown and described in my copending application Serial No. 185,659, filed August 11, 1917.

In order to reproduce sound which is pleasing to the ear and which may be carried a relatively great distance, for example, in a concert hall, it is necessary that the volume, as distinguished from mere loudness of the sound reproducing machine be sufficiently great. This involves the development and reinforcement of the sound waves initiated by the diaphragm so that the recorded sound may be faithfully reproduced and delivered uniformly throughout a large space, without having to use a very large machine.

I have illustrated my invention in connection with a sound reproducing machine 95 preferably of the cabinet type, this invention being adapted to be conveniently mounted in the cabinet below the top thereof as is usual in this type of instrument. The parts of the present invention are preferably made of resonant wood rather than of metal as the tones of reproduced sound developed through resonant wood conduits and amplifiers is fuller and more pleasing than that reproduced through metal conduits. My invention comprises a conduit or distributing chamber 10 preferably mounted in a vertical position, the upper end of which is adapted to receive the end of a tone arm which may be of the style shown 110

in Patent Nos. 1,170,801, and 1,170,802, granted to me February 8, 1916. However, as the tone arm connection does not form part of my invention I shall not describe the same here. The conduit 10 for the greater part of its length is bored as at 11, the cross section thereof being circular. The bore 11 terminates in a cubical sound distributing chamber 12, the cross sectional area of which is slightly greater than the cross sectional area of the bore 11. Connected with the distributing chamber 12 and extending therefrom on each side are the conduits 13, 14, the cross section of which is circular and of less area than the cross section of the chamber 12, and the axes of which are preferably in the same straight line. The conduits 13, 14, have the circular bored portions 15 terminating in substantially cubical chambers 16, which communicate with mechanical throats 17 similar to those disclosed in my Patent No. 1,170,801. Communicating with the throats 17 are a series of orchestral chambers 18, 19, preferably of the type shown in my Patent No. 1,170,800, and communicating with the end-most orchestral sections 19 are the violin resonators 20 which resonators are preferably of the type shown in my Patent No. 1,170,800. I have found by experiment that the volume of sound reproducing machines may be greatly increased for developing fuller and richer tones by connecting the tone arm with a plurality of amplifiers of substantially the construction herein disclosed. The cross sectional areas of the various conduits vary. In the arrangement shown herein the cross sectional area of the cubical distributing chamber 12 at the lower end of the conduit 10 is greater than the cross sectional area of the bore 11 in said conduit. The cross sectional area of the bore 15 of the conduits 13, 14, is less than the cross sectional area of the chamber 12, and the cross sectional area of the cubical chambers 16 is greater than the cross sectional area of the bores 15. It will be noted that I have provided a plurality of openings through which the sound waves travel which openings are of different shapes and sizes. Because of the fact that the conduits are of resonant wood and together with the provision of the conduit openings being of various sizes and forms, it is possible to so develop the sound waves as to deliver at the ends of the resonators reproduced sounds which are as free of mechanical effect as it is possible to make such sounds. The effect of the plurality of amplifiers comprising the parts described is an increase of the volume of the reproduced sound while maintaining the quality, fullness, richness and the tone of the recorded sound. It is to be noted that in the disclosure shown herein I have shown one dis-

tributer 12 as being provided with but two sound outlets 13, 14. However, it is understood that this number may be increased if desired without departing from the scope of my invention.

70

In employing my invention I have found that the volume of the sound reproduced in a machine having a plurality of outlets is greatly increased over that reproduced by a machine having but a single outlet, the needle, sound box and tone arm of each machine being the same. With this arrangement, especially with the restricted orifice in the distributing chamber through which the sound waves flow to the outlets and where the outlets communicate with a single chamber, a greatly increased volume of sound is delivered, the needle scratches eliminated and the sound reproduced in unison. Apparently the vibrations of sound in the cubical chamber are dissipated evenly through each of the outlets, as the delivered sound in each outlet is exactly the same as the sound in the other. Where a sound conduit is employed leading from the tone arm to each of a plurality of outlets without a distributing chamber, the sound delivered is not in unison and the volume is not increased.

80

While I have described more or less precisely the details of construction, I do not wish to be understood as limiting myself thereto, as I contemplate changes in form and the proportion of parts and the substitution of equivalents as circumstances may suggest or render expedient, without departing from the spirit of my invention.

95

I claim:—

1. In a sound reproducing machine, in combination, a substantially cubical distributing chamber, a sound conduit leading to said chamber, a plurality of conduits each connected with said distributing chamber, each conduit having an opening therethrough of a plurality of shapes symmetrically arranged with respect to a transverse plane through the middle of the conduit, and resonators in communication with the ends of the conduits.

105

2. In a sound reproducing machine, in combination, a substantially cubical distributing chamber, a sound conduit leading to said chamber, a plurality of conduits each connected with said distributing chamber, each conduit having an opening therethrough of a plurality of shapes symmetrically arranged with respect to a transverse plane through the middle of the conduit, a mechanical throat in communication with each conduit, resonators, and orchestral sections between the throat and resonators.

110

3. In a sound reproducing machine, in combination, a distributing chamber having a cylindrical central opening terminating in a substantially cubical portion, a plurality

120

125

130

of conduits connected with the cubical portion of said distributing chamber, each conduit having an opening therethrough of a plurality of shapes symmetrically arranged 5 with respect to a transverse plane through the middle of the conduit, and resonators in communication with the ends of the conduits.

4. In a sound reproducing machine, in 10 combination, a distributing chamber having a cylindrical central opening terminating in a substantially cubical portion, a plurality of conduits connected with the cubical portion of said distributing chamber, each conduit having an opening therethrough of a plurality of shapes symmetrically arranged 15 with respect to a transverse plane through the middle of the conduit, a mechanical throat in communication with each conduit, 20 a resonator, and orchestral sections between the throat and resonator.

5. In a sound reproducing machine, in 25 combination, a vertically disposed distributing chamber having a cylindrical central opening terminating in a substantially cubical portion, a plurality of horizontally dis-

posed conduits connected with the cubical portion of said distributing chamber, each conduit having an opening therethrough of a plurality of shapes symmetrically arranged 30 with respect to a transverse vertical plane through the middle of the conduit, and resonators in communication with the ends of the conduit.

6. In a sound reproducing machine, in 35 combination, a vertically disposed distributing chamber having a cylindrical central opening terminating in a cubical lower portion, a plurality of horizontally disposed conduits, each connected with the cubical 40 portion of said distributing chamber, each conduit having an opening therethrough of a plurality of shapes symmetrically arranged with respect to a transverse vertical plane 45 through the middle of the conduit, a mechanical throat in communication with said conduit, resonators, and orchestral sections between the throat and resonators.

Signed at Chicago, Illinois, this 11th day of February, 1919.

FOREST CHENEY.
